UNITED STATES PATENT OFFICE.

JOHN A. RUFFIN, OF MIDDLETOWN, CONNECTICUT, ASSIGNOR TO THE NOISELESS TYPEWRITER COMPANY, OF MIDDLETOWN, CONNECTICUT, A CORPORATION OF CONNECTICUT.

TYPE-WRITING MACHINE.

1,295,212.

Specification of Letters Patent. Patented Feb. 25, 1919.

Application filed March 31, 1916. Serial No. 87,937.

To all whom it may concern:

Be it known that I, JOHN A. RUFFIN, a citizen of the United States, residing at Middletown, in the county of Middlesex and 5 State of Connecticut, have invented certain new and useful Improvements in Type-Writing Machines, of which the following is a full, clear, and exact description, such as will enable others skilled in the art to 10 which it appertains to make and use the same.

This invention relates to typewriting machines and more specifically to improved typewriter escapements.

15 The primary object of the invention is to provide simple and practical means to render the escapement mechanism noiseless when the platen carriage is moved toward line-commencing position.

20 Other objects and advantages will be in part noted hereinafter in connection with a typical embodiment of the invention illustrated in the accompanying drawings.

The invention accordingly consists in the 25 features of construction, combinations of elements and arrangements of parts which will be exemplified in the construction hereinafter set forth, and the scope of the application of which will be indicated in the following claims.

In the drawings—

Figure 1 is a side view of an escapement mechanism associated with portions of a typewriting machine shown in section;

25 Fig. 2 is a perspective view of the escapement;

Fig. 3 is a cross section and plan view of the escapement; and

Fig. 4 is a cross section and side view 40 thereof.

The embodiment of the invention shown in the drawings is illustrated as incorporated in a Noiseless typewriter. It is to be understood, however, that the features of 45 the invention are susceptible of application as well to various other styles of machine.

Referring more particularly to the drawings, there is represented a typewriter having at the rear a traveling platen carriage 1, mounted for longitudinal reciprocation on a shift rail 2 capable of elevation and depression to permit different case

printing. The carriage 1 is provided with a straight rack 3 therebelow in mesh with the teeth of a pinion 4 keyed to a vertical 55 spindle 5 attached through connecting bracket 6 to the shift rail. The escapement is arranged at the lower end of the spindle 5 and comprises, generally, a rotatable pinion or escapement rack 7, the teeth of which 60 coöperate with a movable stepping dog 8 and a relatively fixed holding dog 9 on a dog carrier 10, in turn trunnioned on offset arms 11 of a stamped bracket 12 mounted 65 on a cross piece of the machine frame at 13. The bracket 12 also supports the escapement wheel 7 and its associated parts comprising a friction brake wheel 14, a silencing plate 15 (to be described), and staggered rollers 16 which fit in complementary grooves 17 70 of the spindle 5 to key the escapement wheel to the spindle and thereby insure rotation of the escapement wheel in synchronism with the longitudinal movement of the platen carriage while permitting relative case shifting 75 of the latter.

The dog carrier 10 is provided on its lower side with the movable dog 8 and on its upper side at the extremity of an offset arm 18 with the relatively fixed dog 9. The two 80 dogs mentioned are respectively pivoted at 19 and 20 and extend, in their general direction, substantially at right angles, being normally biased to carry the dogs oppositely by a single retractile spring 21 tensioned between a rear extension 22 of the movable dog 8 and a depending lug 23 of the relatively fixed dog 9.

When the machine is at rest the parts are positioned as shown in Fig. 2, wherein the 85 fixed dog 9 is engaged by a tooth of the escapement wheel 7 to limit movement of the platen carriage in proper position to receive a character imprint. Upon actuation of the escapement either through the universal bar 90 associated with the type levers, or through the space bar, movement is transmitted to the dog carrier 10 through link 24 or link 25 to rock the carrier and elevate the relatively fixed dog 9 out of engagement with the escapement wheel tooth so that said wheel 95 rotates under the influence of the carriage propelling drum spring, and the movable dog 8 is simultaneously raised in a position 100

to be engaged by the succeeding teeth of the escapement wheel. The latter then rotates until dog 8 is limited by a cam stop 26 pivoted on the under side of the dog carrier 5 at 27 and extending within a recess 28 on the rear end of the movable dog. The thus limited position of the movable dog coincides substantially with the normal position of the fixed dog, so that upon released locking of the dog carrier the fixed dog moves to engage and hold the escapement wheel 7, and the movable dog 8 is carried out of engagement therewith and springs silently to its normal position for succeeding operation. 10 15 When the platen carriage is moved to the right, for new lines of writing, the teeth of the escapement wheel 7 would normally tend to force the relatively fixed dog 9 rearward against spring 21, thereby permitting reverse rotation of the escapement wheel, but entailing a rapid and objectionable clicking sound due to the spring pressed striking of the fixed dog against the successive escapement wheel teeth. There is accordingly 20 25 provided the plate 15 above the escapement wheel and loose on the supporting hub 29 thereof. This plate has an offset rear cam piece 30 and a side cut-away portion or recess 31 within which is arranged a stud 32 30 35 on the bracket 12. A friction ring 33 is positioned between the plate 15 and hub 29 and exerts a tendency on the plate to rotate with the wheel 7 in either direction. Movement of the plate, however, is limited by its engagement at the sides of recess 31 with the stud 32 described.

During letter spacing movement of the carriage, the offset cam 30 of the silencing plate 15 is disposed in advance of and out 40 of contact with the fixed dog 9. When, however, the carriage is moved to the right, the plate 15 is rotated, due to its frictional mounting on the hub 29, so that the cam piece 30 engages and retracts the dog 9 out 45 of engagement with the escapement wheel teeth and holds the dog in this position as long as the carriage is moved toward line-commencing position. The dog 9 is thus held against the tension of its spring 21 and 50 the escapement wheel is free to rotate silently.

Immediately upon cessation of the reverse carriage movement, the plate 15 is again rotated to carry the cam piece 30 out 55 of the way of the fixed dog so that the normal letter space movement of the carriage is permitted and the silencing means is held in abeyance until its operation is again required.

60 As many changes could be made in the above construction and many apparently widely different embodiments of this invention could be made without departing from the scope thereof, it is intended that all

matter contained in the above description 65 or shown in the accompanying drawings shall be interpreted as illustrative and not in a limiting sense.

Having described my invention, what I claim as new and desire to secure by Letters 70 Patent is:

1. In a typewriting machine, in combination, an escapement rack, a controlling dog therefor spring-pressed thereagainst, said parts being relatively movable and one 75 adapted to operate with the traveling carriage of the machine in both directions, and means to maintain said parts out of contact when moved relatively in one direction.

2. In a typewriting machine, in combination, a traveling carriage, an escapement rack therefor, a holding dog to engage the teeth of said rack for limiting the letter space movement of said carriage, and means controlled by said rack in accordance with 80 the direction of its movement and controlling said dog to permit a free movement of said rack opposite to its letter space movement.

3. In a typewriting machine, in combination, a spring-propelled carriage, a rotatable escapement rack operating therewith, a pivoted holding dog and a pivoted stepping dog for said rack, said holding dog being 90 spring-pressed toward said rack and bodily 95 movable to free the latter for engagement with said stepping dog, and means to move said holding dog out of contact with said rack independently of its bodily movement.

4. In a typewriting machine, in combination, a spring-propelled carriage, an escapement wheel operating therewith, a holding dog mounted for pivotal and bodily movement and normally urged to engage said wheel, and means frictionally associated 100 with said wheel to move said dog pivotally to free said wheel when the latter is rotated during movement of the carriage opposite to its spring-propelled direction.

5. In a typewriting machine, in combination, an escapement wheel, a holding dog spring-pressed thereagainst, a member tending 110 to rotate with said wheel in both directions and engaging said dog when rotated in one direction, and means to limit rotation 115 of said member in both directions independently of said wheel.

6. In a typewriting machine, in combination, a carriage movable longitudinally for letter spacing and vertically for case shifting, a rotatable escapement wheel to control letter spacing movement of said carriage, connecting means between said parts to insure simultaneous letter spacing movement while permitting independent case shifting 120 movement, a holding dog for said wheel adapted to engage its successive teeth, a member mounted for limited rotation about 125

the axis of said wheel and having a part overlapping the teeth thereof adjacent said dog; and means to insure rotation of said member to interpose said part thereof between said dog and the teeth of said wheel while said carriage is moved toward line-commencing position.

In testimony whereof I affix my signature, in the presence of two witnesses.

JOHN A. RUFFIN.
